UNITED STATES PATENT OFFICE.

WILLIAM NEWBOLD, OF EAST CLEVELAND, OHIO.

BOLT-GUARD.

SPECIFICATION forming part of Letters Patent No. 270,972, dated January 23, 1883.

Application filed October 30, 1882. (No model.)

To all whom it may concern:

Be it known that I, WILLIAM NEWBOLD, of 5
East Cleveland, in the county of Cuyahoga and
State of Ohio, have invented certain new and
useful Improvements in Bolt-Guards; and I
do hereby declare the following to be a full,
clear, and exact description of the invention,
such as will enable others skilled in the art to
which it pertains to make and use the same.

10 My invention relates to an improved bolt-
guard; and it consists of a new device for mak-
ing a door-bolt more secure as against burglars.

15 In the drawings, Figures 1 and 2 are plan
views, representing different modes of making
the device. Fig. 3 is an isometric view of the
device constructed according to my invention.

A represents a plate, of any suitable metal,
with serrated edges, as shown at D.

20 The dotted lines a show where the plate is to
be bent in forming it into the box shape that
it assumes when it is completed, as shown in
Fig. 3.

25 B represents the casing of the bolt, and may
be attached directly to the plate A, as shown
in Fig. 1; or the case B may be first attached
to the plate C, as in the ordinary way of mak-
ing door-bolts, and then attached to the plate
A, as shown in Figs. 2 and 3.

30 E represents the bolt, and A, Fig. 3, the
guard when completed and combined with the
bolt.

The operation of my new device is as fol-
lows: The usual means employed by burglars
to unfasten a door secured by a bolt is to bore

a small hole through the door and insert a 35
bent rod or wire, with which they engage the
bolt and draw it back out of its fastening.
With my invention the bolt is protected by the
box-shaped guard surrounding it, as hereto-
fore described, making it difficult to introduce 40
through a hole in the door a rod or wire that
has been first bent in such shape that it will
engage the bolt; and the serrated edges of the
guard render it extremely difficult to so oper-
ate a rod or wire as to withdraw the bolt from 45
its fastening, even if the rod or wire could be
brought in contact with the bolt. Hence it
will be seen that the application of my inven-
tion makes a valuable safeguard against all
burglarious attempts on a door fastened with 50
a bolt secured as aforesaid.

What I claim is—

1. A door-bolt having a guard-casing secured
thereto, said casing being formed with side
and end walls that project outwardly from the 55
bolt, substantially as set forth.

2. A door-bolt having a guard-casing secured
thereto, said casing being formed with side
walls having serrated edges, substantially as
set forth.

60 In testimony whereof I sign this specifica-
tion, in the presence of two witnesses, this 21st
day of October, 1882.

WILLIAM NEWBOLD.
